STAKE POCKET FOR CARS

Roy A. Lewis, Bethlehem, and Charles Schenck,
Coopersburg, Pa., assignors to Bethlehem Steel
Company, a corporation of Pennsylvania

Original application December 29, 1934, Serial
No. 759,704. Divided and this application
March 20, 1936, Serial No. 69,846

6 Claims. (Cl. 105—390)

This invention relates to flat car underframe structures or the like for railway cars, and is particularly directed to the stake pockets and the arrangement and manner of forming and attaching said stake pockets to the underframe structure, and is a division of our copending application entitled "Welded car underframe", filed December 29, 1934, Serial No. 759,704.

The stake pockets for receiving the lower ends of the stakes in position in spaced relation along the sides and ends of the car have been formed heretofore of cast or pressed metal and usually attached to the flat side surfaces of the side or end sills of the car underframe by means of bolts or rivets. When the car is loaded the stake pockets are subjected to enormous strain produced by the leverage pressure of the lading on the extending stakes of the car, which results in the connections of the stake pockets with the underframe becoming loose, or the stake pockets breaking off. The loosening of the stake pockets further has the disadvantage of allowing moisture to collect around the bolted or riveted connections thereby allowing corrosion to set in very rapidly.

One of the objects of our invention relates to forming the stake pockets of rolled sheet metal adapted to be attached directly to the car underframe by welding.

Another object of our invention relates to forming the stake pockets in such a manner that they will be more securely braced when attached to the car underframe.

A further object of our invention resides in the manner of reinforcing the intermediate portion of the stake pocket.

Another object of our invention is to provide a stake pocket that can be attached to a flanged or flat surface of the car underframe.

Having thus given a general description of the objects of our invention we will now in order to make the invention more clear refer to the accompanying two sheets of drawings which form a part of this specification and on which like characters of reference indicate like parts;

Figure 1 is a top plan view of slightly more than one-half of a car underframe illustrating the application of our invention.

Fig. 2 is a detail top plan view of a portion of a car side sill with one of our improved stake pockets attached thereto drawn on a larger scale.

Fig. 3 is a longitudinal section of the portion shown in Fig. 2 taken on the line 3—3 of Fig. 4.

Fig. 4 is a side elevation of the enlarged portion shown in Fig. 2.

Fig. 5 is a vertical section taken on the line 5—5 of Fig. 4, and

Fig. 6 is a vertical section through the end sill taken on the line 6—6 of Fig. 1.

Referring now to the various characters of reference on the drawings the numeral 1 indicates the car underframe as a whole, 2 the center sills, 3 the side sills, 4 the bolster, 5 the cross ties or bearers and 6 a cover plate attached to the top edge of the end sill 7 and adapted to extend inwardly therefrom and provided with a flanged edge as at 8, the lower end of which is bent inwardly at right angles thereto and adapted to form a seat for supporting the end of the car floor.

As illustrated in the drawings the side sills 3 are constructed of rolled I-sections with flanges 9 extending laterally therefrom along the top and bottom edges, although these side sill members may be of other section, as channels, Z-bars, or angles, or they may be made of pressed or of cast metal if desired without departing from the spirit of our invention.

The stake pockets attached to the side sills 3 of the underframe at spaced intervals are formed of rolled pressed sheet metal, each having a U-shaped portion 10 forming the stake pocket, the legs 11 of which are parallel for a portion of their length and connected together by a reinforcing rib 12, which is welded to the legs 11 as at 13. The ends of the legs 11 are formed with outwardly inclined or splayed extensions 14 having their ends welded to the web of the side sill as at 15. The upper surfaces of the leg extensions 14 are inclined, or shaped to conform to the contour of the underside of the upper outwardly extending flange of the side sill and is welded thereto as at 16.

In forming the extensions 14 of the legs splayed in the manner shown, a more desirable bracing effect is obtained than if the legs were made straight for the entire length. To further stiffen and brace the stake pockets laterally, brackets 17 formed of plate metal are welded to the opposite sides of the pockets at an intermediate point as at 18, the inner ends of said brackets being welded as at 19 to the top of the side sills 3. By this construction a very strong and rigid construction is obtained, the stake pockets being substantially integrally connected to the side sills will not become loose and allow moisture to collect and produce corrosion between the connections as in the case where bolts or rivets are used.

The stake pockets 20 at the ends of the car are

formed and attached in a somewhat different manner. These stake pockets are U-shaped, the legs being parallel to each other throughout their entire length. The ends of the legs are welded as 5 at 21 directly to the inner face of the end sill 7, the rear end of the stake pockets engaging the vertical wall of the flange 8 of the cover plate 6 and welded thereto as at 22.

Openings 23 are formed in the cover plate 6, 10 which registers with the stake pockets. The upper end of the stake pockets are adapted to engage the under side of the cover plate 6 and is welded thereto as at 24.

In this construction a very rigid connection is 15 obtained and the stake pockets are securely held in position between the rear wall of the end sill 7 and the vertical wall of flange 8. The sides of the openings 23 in the cover plate 6 further help to support the stake when in position.

20 As illustrated the stake pockets are formed of pressed metal, but they can be formed of cast metal if desired and then welded to the under-frame in the manner above described.

Although we have shown and described our invention in considerable detail, we do not wish to be limited to the exact construction shown and described, but may use such substitutions, modifications or equivalents thereof, as are embraced within the scope of our invention, or as pointed 30 out in the claims.

Having thus described our invention what we claim as new and desire to secure by Letters Patent is:

1. A car underframe, the combination with the 35 end sill, of U-shaped stake pockets formed of pressed plate metal having the edges of its legs welded to the inner side of the end sill, a cover plate secured to the top of the end sill and extending inwardly therefrom over the top ends of 40 the stake pockets and welded thereto, and a flange extending downwardly from the inner edge of the cover plate in spaced relation with the end sill and welded to the back of each stake pocket.

2. A car underframe, the combination with the 45 end sill, a cover plate secured to the top of the end sill and extending inwardly therefrom, a flange extending downwardly from the inner edge of the cover plate in spaced relation with the end sill, and a U-shaped stake pocket interposed between the inner side of the end sill and the flange 50 of the cover plate, said stake pocket being welded to the inner surface of the end sill and the flange of the cover plate.

3. A car underframe, the combination with the 55 end sill, a cover plate secured to the top of the end sill and extending inwardly therefrom, a flange extending downwardly from the inner edge

of the cover plate in spaced relation with the end sill, U-shaped stake pockets interposed between the inner side of the end sill and the flange of the 5 cover plate, said stake pockets being welded to the inner surface of the end sill and the flange of the cover plate, an opening in the cover plate registering with each stake pocket, and a welded connection between the cover plate and the top of the stake pockets.

4. A car underframe, the combination with the 10 end sill, a cover plate secured to the top of the end sill and extending inwardly therefrom, a flange extending downwardly from the inner edge 15 of the cover plate in spaced relation with the end sill, said flange having its lower end bent inwardly at right angles thereto adapted to form a seat for supporting the end of the car floor, and U-shaped stake pockets interposed between the inner side of the end sill and the flange of the cover plate and welded to the inner face of the end sill 20 and the flange of the cover plate.

5. A car underframe, the combination with the end sill, a cover plate secured to the top of the end sill and extending inwardly therefrom, a flange extending downwardly from the inner edge 25 of the cover plate in spaced relation with the end sill, said flange having its lower end bent inwardly at right angles thereto adapted to stiffen the lower edge of the flange and form a seat for supporting the end of the car floor, U-shaped 30 stake pockets interposed between the inner side of the end sill and the flange of the cover plate having the ends of their legs welded to the inner surface of the end sill, and a welded connection between the stake pockets and the cover plate and 35 its flanged edge.

6. A car underframe, the combination with the end sill, a cover plate secured to the top of the end sill and extending inwardly therefrom, a flange extending downwardly from the inner edge 40 of the cover plate in spaced relation with the end sill, said flange having its lower end bent inwardly at right angles thereto adapted to stiffen the lower edge of the flange and form a seat for supporting the end of the car floor, U-shaped stake pockets 45 interposed between the inner side of the end sill and the flange of the cover plate, said stake pockets being welded to the inner surface of the end sill and the flange of the cover plate, an opening in the cover plate registering with each stake 50 pocket, a welded connection between the cover plate and the top of each stake pocket, and a welded connection between each stake pocket and end sill and the flange of the cover plate.

ROY A. LEWIS.
CHARLES SCHENCK.
